CAMERA LENS MOUNT

Frederick W. Hertzler, Detroit, Mich., assignor, by mesne assignments, to Sylvania Electric Products Inc., a corporation of Massachusetts

Application August 20, 1956, Serial No. 42,673

Term of patent 14 years

(Cl. D61—1)

Fig. 1

Fig. 2

Figure 1 is a side elevational view of a camera lens mount, showing my new design, the opposite side having substantially the same appearance; and

Figure 2 is a front elevational view thereof, the rear view being essentially only the smaller end of the circular mount and therefore not illustrated.

I claim:

The ornamental design for a camera lens mount, substantially as shown and described.
